(57) CLAIM

The ornamental design for a rope light with battery housing, as shown and described.

DESCRIPTION

FIG. 1 is a perspective view of an embodiment of a rope light with battery housing;

FIG. 2 is a top plan view thereof;

FIG. 3 is a right elevational view thereof;

FIG. 4 is a left elevational view thereof;

FIG. 5 is a bottom plan view thereof;

FIG. 6 is a rear side elevational view thereof; and,

FIG. 7 is a front side elevational view thereof.

The rope light with battery housing is shown with symbolic breaks in its length.

The appearance of any portion of the article between the break lines forms no part of the claimed design.

The broken lines shown in the drawings symbolize the emitting of the light.
